UNITED STATES PATENT OFFICE.

JEROME STIVERS, OF NEW ROCHELLE, NEW YORK.

DESIGN FOR A CLIP.

SPECIFICATION forming part of Design No. 26,639, dated February 16, 1897.

Application filed November 18, 1896. Serial No. 612,633. Term of patent 14 years.

To all whom it may concern:

Be it known that I, JEROME STIVERS, a citizen of the United States, residing at New Rochelle, in the county of Westchester and State 5 of New York, have invented and produced a new and original Design for Clips, of which the following is a specification.

The figure in the drawing is a perspective view of a clip embodying the invention.

10 The leading feature of my design consists in the clip, provided with spurs projecting from the inner faces of the yoke and the cross-bar, and also in extensions projecting from the edges of the yoke.

15 In the drawing, A designates the yoke, B the cross-bar connecting the ends of the yoke, and C C the nuts securing the cross-bar on the ends of the yoke.

The yoke A in configuration is substantially U-shaped. Its ends are shaped to form 20 screw-threads a' a'. From the inner face a² of the flat portion of the yoke spur-shaped projections a³ a³ extend. The edges of the

substantially flat portion a are shaped to form extensions a⁴ a⁴, as shown in the drawing. In these extensions a⁴ a⁴ are apertures a⁵ a⁵. 25

The configuration of the cross-bar B is substantially that of a parallelopipedon with its upper corners rounded. In its ends are apertures b b, adapted to register with the screw-threaded portions of the yoke. The inner face b' has a spur-like projection b² extending 30 from the same.

Having thus described my invention, what 35 I claim, and desire to secure by Letters Patent, is—

The design for a clip substantially as herein shown and described.

In testimony whereof I hereunto affix my 40 signature in the presence of two witnesses.

JEROME STIVERS.
